UNITED STATES PATENT OFFICE.

CHARLES B. SMITH, OF NEW YORK, N. Y.

TELEPHONE.

SPECIFICATION forming part of Letters Patent No. 741,283, dated October 18, 1903.

Application filed March 6, 1899. Renewed October 22, 1902. Serial No. 128,246. (No model.)

To all whom it may concern:

Be it known that I, CHARLES B. SMITH, a citizen of the United States, residing in New York city, county and State of New York, have invented certain new and useful Improvements in Telephones, of which the following is a specification.

My invention relates more particularly to the class of telephone systems comprising a central office and a party-line leading therefrom on which are located a plurality of subscribers' stations; and one of the objects of my invention is to enable any subscriber on a party-line to call central and also to prevent one subscriber from calling at the same time that another is using the line. In carrying out this portion of my invention I provide a circuit leading from ground at central through the various stations, and in each station I provide electrical devices arranged so that if the line is clear and closed to ground at central the telephone-receiver-supporting lever in a station can operate when the receiver is removed from the same to close a circuit and produce a call or signal at central, but if the line is broken at central the lever will be prevented from closing such circuit.

Another portion of my invention relates to improved means for enabling an operator at central to call any desired subscriber on a party-line without producing a signal in any other station on a party-line and to establish a circuit in each station in connection with conductors that pass from central to enable a calling-subscriber's telephone to be connected with such conductors.

Another object of my invention is to provide an improved plug cord-circuit wherein a battery is bridged across two of the conductors and the primary coils of two induction-coils are included in said bridge and the secondary coils of such induction-coils are also bridged across said conductors.

The invention further consists in the novel details of improvement hereinafter more fully set forth and then pointed out in the claims.

Reference is to be had to the accompanying drawing, which is a diagrammatic view of a telephone system embodying my invention.

In the accompanying drawing the letter A indicates a central office at which are located suitable telephone and circuit-controlling de-

vices, and B C are stations on a party-line circuit, 1 2 3 being conductors leading from central to and through the subscribers' stations. There may be any desired number of such stations on a circuit. At the central office the conductor 1 connects with a contact 4 of a spring-jack 5, and the contact 4 is in normal engagement with a contact 6, from which a conductor 6 7 leads through a battery 8 to a contact 9, that is in normal engagement with a contact 10, connected by a conductor 11 with ground at 12. Thus in the normal positions of these parts there will be a circuit passing over conductor 1 from all the stations to ground 12 at central. This circuit with appropriate electrical devices is for the purpose of enabling the lever or hook 13 of the receiver 14 in each station to establish a circuit for producing a signal at the central office if the line to central is not in use and to prevent such circuit from being established if the line to central is in use. For these purposes at each station the line 1 is connected by a branch 15 with the lever 13, which lever has a contact 16, normally out of engagement with but adapted to engage a contact 17, that is connected with a conductor 18, on which is located a magnet 19, the conductor 18 leading to ground 20. The arrangement is such that when the receiver hangs on lever 13 the circuit will be broken at 16 17; but when the receiver is removed from the lever the spring 13^a can move said lever to cause engagement of contacts 16 17. To prevent the lever 13 from closing circuit through the receiver if the line 1 is in use, the armature 21 of magnet 19 carries a detent 22, that is adapted to engage and arrest the upward movement of lever 13 if the magnet 19 is not energized. I have shown the armature 21 as passing through an aperture 13^b in lever 13, so that the detent 22 in its normal position will lie in the path of lever 13. Thus if the circuit over line 1 is closed in central at 9 10 and the subscriber at a station removes receiver 14 from its lever the lever will rise and cause contacts 16 17 to engage, whereupon a circuit will be established to central from 20 at the calling-station through 19, 18, 17, 16, 15, 1, 4, 6, 7, 8, 9, 10, and 11 to ground at 12. Magnet 19 will now attract armature 21, whereupon detent 22 will be moved out of the path of lever 13 to enable the latter to move the

full distance into engagement with a contact 23; but if the circuit over line 1 at central is broken (because the line is in use by some other subscriber or by the operator at central) magnet 19 cannot operate, and therefore 5 detent 22 will remain in the path of lever 13, and thus prevent the lever from engaging contact 23. When, however, the line 1 is closed at central, so that the lever 13 of a calling-sub- 10 scriber's station can make engagement with contact 23, a closed metallic circuit can be established between the calling-station and central to produce a call at central as follows: The conductors 1 and 3 are utilized in forming 15 such closed metallic circuit, and while the line 3 is normally closed from central through all the stations it is adapted to be broken into sections in each station and the lines 1 and 3 are adapted to be electrically 20 connected at central and at the subscribers' stations. At central the line 3 connects with a contact 24, that is in normal engagement with a contact 25, from which a conductor 26 leads to a contact 4^a of jack 5, and a contact 25 27 in normal engagement with contact 4^a is connected by a conductor 28 to a magnet 29, from which a conductor 30 leads to conductor 7. The sections of line 3 at each station lead 30 to a movable contact 31, that is in normal engagement with a contact 32, which is connected by a conductor 33 with the receiver 14 thereat, 34 being a transmitter, and from receiver 14 a conductor 35 connects with contact 23. The magnet 29 at central has two functions, one 35 of which is to operate contact 9 to break circuit at 9 10 and the other to close a local circuit at central to produce a signal or call. For these purposes I have shown the contact 9 as carried by but insulated from armature 29^a, and from said armature a conductor 36 leads through a battery 37 to a lamp or other signaling instrument 38, from which a conductor 39 leads to a contact 40, adapted 40 to be engaged by armature 29^a, so that when magnet 29 is energized circuit will be broken at 9 10 over line 1 to prevent another subscriber from obtaining a circuit to ground 12 at central and circuit at 29^a 40 will be closed to produce a signal in instrument 38 at central. 50

If a subscriber at the first station from central on the circuit, as B, desires to call central, he removes his receiver 14 from lever 13, which causes contacts 16 17 to engage, and if 55 the line 1 is not in use magnet 19 will operate detent 22 to enable lever 13 to close circuit at 23, whereupon a closed metallic circuit between the calling subscriber and central through magnet 29 will be established as follows: from lever 13 at the calling-station through 15 and over line 1 to contact 4 at central, thence through 6 7, battery 8 30, magnet 29 28 27 4^a 26 25 24, and line 3 to contact 31 at station B, thence through 32 and 60 33 to receiver 14, thence through 35 and 23 back to lever 13. Magnet 29 will now be energized to break circuit at 9 10 and to close circuit at 29^a 40 to produce a call. If a subscriber at a station farther along the circuit from central than B had called central, 70 the circuit over line 3 would have passed through station B. The line 3, as before stated, is adapted to be broken into sections in each station, for which purpose the part of the line 3 that leads into a station from 75 central connects with contact 31, as stated; but the part of line 3 that passes from one station to another, as from B to C, connects with a contact 41, that is in normal engagement with contact 31, thus forming a normally through line in each station at 31 41, (having a branch or spur extending from 32, through 33, 14, and 35 to contact 23 in each station.) Thus if the subscriber at station 80 C had called central the closed metallic circuit before described would have been substantially the same excepting that in the intermediate station B the circuit over line 3 instead of passing to contact 23 at B would have passed from contact 31 to contact 41 85 and thence over line 3 to station C, where it would pass through 32, 33, 14, and 35 to contact 23 and thence to lever 13. The circuit over line 3 will likewise pass through contacts 41 and 31 at all stations between central and 90 the calling-station. If while a calling subscriber is producing a call at central another subscriber desires to call central and removes his receiver 14 from its hook, there will be no circuit for his magnet 19, as the circuit is 95 broken at 9 10 at central. When a call is received, however, the operator at central in responding places a plug 42 in jack 5, which acts to move contacts 4 and 4^a out of engagement with contacts 6 and 27. This of course 100 breaks the circuit of magnet 29 and allows contacts 9 and 10 to again engage; but as the circuit over line 1 is now broken at 4 6 another subscriber cannot establish a circuit over line 1 to ground at central for his magnet 19, and 105 therefore cannot produce a call or establish circuit over line 1 while the plug remains in the jack unless permitted so to do by the operator at central. 110

The contacts 42^a of two plugs 42 are connected by a conductor 44, and the contacts 42^b are connected by a conductor 49. The contact 42^a is adapted to engage contact 4 in jack 5 to break circuit at 4 6, and the contact 42^b is adapted to engage contact 4^a of jack 5 120 to break circuit at 4^a 27. The conductors 44 and 49 contain in a bridge a battery 45 and the primaries of two repeating or induction coils 46, one on each side of the battery, and the secondary coils 46^a are bridged across 125 conductors 44 49 independently of the battery 45, as by conductors, preferably leading to a condenser 46^b. The receiving-telephone 43 is adapted to be bridged across conductors 44 49 by means of a push button or key 47, acting 130 to press a contact 47^a into engagement with a contact 47^b, connected with conductor 44, and a spring 48 into engagement with a contact 48^a, connected with conductor 49, the

springs 47^a 48 being connected with receiver 43. When the plug is in the jack, the battery 45 and the repeating-coils are connected with lines 1 and 3 for the telephone instruments. The induction-coils shown have a core and are adapted to be used as impedance-coils.

Suppose the operator at station C calls central. In response the operator at central 10 places plug 42 in jack 5 and operates key 47. A closed metallic circuit between the calling subscriber and central will thus be established as follows: from lever 13 at C through 15 to line 1, thence to 4 at central through 15 42^a 44 and through receiver 43 to 49, thence through 42^b, 4^a, 26, 25, and 24 to line 3, thence over line 3 (through contacts 31 and 41 at B) to 31 at C, thence through 32 and 33 to receiver 14, and through 35 and contact 23 back 20 to lever 13 at C. The battery 45 supplies current for the circuit, and the fluctuations of the current through coils 46 induce current in coils 46^a, which traveling over the circuit produces the effect of an induced current in the 25 receiving-telephones. It will be seen that this induced current passes to the circuit independently of battery 45. The condenser 46^b in the circuit of the secondary coils 46^a prevents the leakage of current from battery 30 45 through the secondary coils. After the operator at central ascertains what subscriber is wanted he is to call such subscriber.

The arrangements I have shown for enabling the operator at central to call the desired subscriber without calling any other subscriber on the circuit are as follows: The line 2, which I term an "operating-line," is utilized for establishing a circuit in the desired subscriber's station for a signaling instrument thereat in connection with line 1, over which a call is produced. At each station a suitable signaling instrument 55 is connected with line 15, and line 15 leads to a contact 56. The contact 56 is normally out of 45 engagement with but is adapted to be engaged by a contact 57, that is normally out of engagement, but adapted to engage a contact 58, connected by a conductor 59 with ground at 60 in each station, so that when contact 57 50 engages contacts 56 58 the circuit in the station for the signaling instrument 55 will be from line 1 through 15, 55, 56, 57, 58, and 59 to ground 60. The contact 57 is to be operated by current on line 2. The line 2 is not 55 normally closed through the subscribers' stations, but is broken into sections in said stations adapted to be connected into a through-line, for which purpose the part of the line 2 that leads into a station from central is 60 shown connected with a contact or armature 61, that is in normal engagement with a contact 62, connected by a conductor 63 with ground, being shown connected with conductor 59 and thence to ground 60. 64 is a magnet 65 net in each station located on the part of line 2 that leads into the station, which magnet is shown having poles at both ends, one

of which is adapted to attract armature 61, (which is a dead armature having no spring,) and the other pole is adapted to attract an 70 armature 65, that is connected with but insulated from contact 57, so as to operate the latter, and provided with a spring 66, that acts to normally hold contacts 56, 57, and 58 out of engagement. The armatures or contacts 61 and 65 are shown connected by a conductor 67. The conductor 2 in each station is also connected by a spur 2^a with contact 57, by which a temporary ground for the section of line 2 and magnet 64 in a station 80 can be established from 2 through 2^a, 57, 58, and 59 to ground 60. Each section of line 2 in a station is also connected with a contact 68, that is on the side of the magnet toward central and adapted to be engaged by contact 85 or armature 61 when magnet 64 is energized. The section of line 2 that leads from a station is in the station from which it leads connected with a contact 69, that is in normal engagement with armature or contact 65. 90 The parts 61, 68, 67, 65, and 69 are for the purpose of joining two sections of line 2 together in a station to establish a through-line out of such sections.

If the operator at central desires to call 95 the first station on a circuit, as B, he sends an impulse over line 2, which passes through magnet 64 at B and thence through 62, 63, and 59 to ground 60. Magnet 64 thereupon draws armatures 61 and 65, breaking circuits at 61 62 and at 31 32 41 and closing circuit at 61 68, and armature 65 breaks circuit at 69 and closes circuit at 2^a 56 57 58. Thereupon a temporary ground for the first section of line 2 will be established at B from 105 2 through 2^a, 57, 58, and 59 to 60 to keep magnet 64 energized to hold a circuit for the calling instrument 55 closed at 56 57 58. The operator at central then sends an impulse over line 1, which passes through 15, 55, 56, 110 57, 58, and 59 to ground 60 at B, producing a call. The operator next breaks the current from line 2, and the spring 66 causes armature 65 to return, thereupon closing circuit at 65 69 and breaking circuit at 56 57 58. 115 Two sections of line 2 at station B will now be joined together from the part of line 2 leading into the station through 68, 61, 67, 65, and 69 to the next section of line 2 leading from station B. It will be observed that 120 the circuit of line 3 is still broken in station B at 31 41 and that the circuit for receiver 14 at B is broken at 32 31. It will be therefore necessary for the operator at central to restore circuit at 31 32 41, as will be hereinafter explained. If the operator at central had 125 desired to call station C instead of B, he would have sent one impulse over line 2 to station B, as before described; but before sending current over line 1 he would break 130 the impulse over line 2, whereupon two sections of line 2 at B would be joined together, as described, and he would thereupon send another impulse over line 2, which would

pass through station B to ground 60 at station C, whereupon magnet 64 at C would attract armatures 61 and 65, breaking circuit at 61 62 and establishing the temporary ground 5 at 67 58 to keep magnet 64 energized and closing the circuit of the signaling instrument 55 at 56 57. Thereupon current will be sent over line 1, which will pass to ground 60 at station C, (not passing to ground 60 at 10 station B because of the break in the circuit at 56 57,) and he will thereupon discontinue the current on line 2, whereupon spring 66 will move armature 65 to close circuit at 65 69 and break circuit at 56 57 58. 15 So, also, if there are more stations than one on the circuit between central and the station to be called an impulse will be sent over line 2 for each station to and including the station desired, whereupon in each intermediate 20 station the sections of line 2 will be joined into a through-line to ground 60 at the station desired. The next step is to restore armature or armatures 61 to normal position to reestablish circuit at 61 62 and at 25 31 32 41, the arrangements for which are as follows: At each station is a contact 70, that is adapted to be engaged by contact 31 when armature 61 is attracted by the corresponding magnet 64, and from contact 70 a conductor 71 leads through a magnet 72 to ground 30 73. As each magnet 64 is operated the line 3 is broken into sections in each station so operated, and a ground is therewith established by the closing of the circuit at 31 70 for the corresponding magnet 72. To restore the parts that have been operated, the operator at central sends a prolonged impulse over line 3, which passes through 31, 70, 71, and 72 to ground 73 at the first station from central, 35 whereupon that magnet attracts armature 61, which breaks circuit at 61 68 and 31 70 and closes circuit at 61 62 and at 31 32 41, whereupon the current will flow on over line 3, performing the same operations in each station 40 in which the devices have been operated in reaching the station to be called, so that the calling subscriber will have a circuit for the receiver in his station from 13 through 23, 35, 110 45 14, 33, 32, and 31 to line 3. When the called 50 subscriber removes his receiver from its lever, the latter would be prevented from engaging contact 23, caused by the presence of plug 42 in jack 5; but to form a ground at central for magnet 19 at the called station 55 over line 1 the operator at central presses key 47 to close circuit at 47^a 47^b and move contact 48 into engagement with a contact 52, that leads by a conductor 53 to ground, as at 54, and also into engagement with contact 60 48^a, connected with conductor 49, whereupon a circuit from the called station over line 1 to ground at central will be established as follows: from 20 at the called station through 19 18 17 16 15 to line 1, thence to contact 4 65 and through 42^a 44 and battery 45 to 49, thence through 48^a, 48, 52, and 53 to ground 54. Magnet 19 at the called station will now

attract its armature 21 and cause detent 22 to allow lever 13 to engage contact 23. If the calling and called subscribers are on the same party-line, their receivers 14 will now be in a closed metallic circuit established as follows: from lever 13 at station B through 23, 35, 14, 33, 32, 31, and 41 thereat to line 3, thence to contact 31 at station C through 31, 32, 33, 14, 35, 23, lever 13, and conductor 15 to line 1, thence over line 1 to conductor 15 at B and back to lever 13. The telephones for stations B and C will now be in multiple. The battery at 45, located at central, supplies 80 current for the transmitters, as heretofore described. If there are any stations on a circuit between the calling and the called subscribers, the circuit will pass through such intermediate stations unbroken over line 1 85 and through contacts 31 and 41 of line 3. If the calling subscriber is on a different circuit from the called subscriber, the operator at central may connect the jacks 5 of such two circuits, and the arrangement is such 90 that the battery 45 will operate on both circuits.

It will be understood that a party-line organized as described can be utilized with other similar party-lines or other well-known 95 telephone-circuits leading to a jack at central.

Any suitable means may be provided to notify the operator at central to disconnect the lines, such as magnet *a* on the plug-cord circuit adapted to close a local circuit *b* of a 100 lamp or other signaling instrument *c*. While a subscriber's telephone is connected with conductors 1 3 the lamp *c* will glow; but as soon as a subscriber hangs his receiver upon lever 13, and thus breaks circuit at 13 23, 105 magnet *a* will be deenergized and the light will go out, thus indicating to the operator at central that the subscriber has finished using the line.

Any suitable means can be provided at central for sending the appropriate impulses over the lines 1 2 3 to select and call the desired station. The devices I have shown for the purpose are as follows:

At central is a toothed wheel 75, whose 110 shaft 76 may be suitably journaled and provided with a handle 77, and 78 is an annular contact carried by insulation 79, attached to said wheel. The wheel has a long tooth 75^a and a series of shorter teeth 75^b upon its periphery.

80 is a contact suitably supported and in engagement with contact 78 and connected by a conductor 81 with a battery 82, from which a conductor 83 extends to ground 84. 125 The contact 78 is connected by a conductor 85 with a movable contact or switch 86, pivotally carried upon the insulation 79 or otherwise insulated from but carried by wheel 75.

87 is a contact carried by wheel 75 and 130 adapted to be engaged by contact 86, the contact 87 being in electrical connection with a conductor 88, as by a contact 88^a, connecting 88 and 75.

90 is a stop carried by insulation 79 or otherwise carried by and insulated from wheel 75, which is adapted to be engaged by the contact 86.

- 5 The contact or switch 86 is adapted to be moved into engagement with contact 87 and stop 90 during the rotations of wheel 75. For this purpose there is a stop or pin 91 located at the starting-point, with which switch 86 10 comes into engagement when wheel 75 returns to the starting or home point, whereby switch 86 will be moved into engagement with stop 90, which is the normal position of the parts. To cause switch 86 to engage contact 87, I 15 provide a plug 92, which is adapted to be inserted in apertures 93 in a plate or ring 94, forming part of the mechanism. The apertures 93 are at suitable distances apart, and each one corresponds to a station on a party-line, and when the plug 92 is in one of these apertures and wheel 75 is rotated the switch 20 86 will engage such plug and will thereby be moved into engagement with contact 87, and the rotation of wheel 75 will be stopped. By 25 preference I provide insulation 86^a on switch 86 to engage the plug 92.

The teeth upon wheel 75 are adapted to make and break circuit through the operating-line 2, and for this purpose I have shown 30 a contact 95 connected with line 2 and a contact 96 connected with conductor 88, which contacts are adapted to make and break circuit under the influence of the teeth of wheel 75. I have shown a rocker-arm 97 pivoted 35 at 98 and adapted to be operated by the teeth 75^a 75^b of wheel 75 to make and break circuit between the contacts 95 and 96, insulation 97^a being provided between 96 and 97. When switch 86 engages contact 87, the circuit for 40 line 2 at central will be from ground 84, through 83, battery 82 81 80 78 85 86 87 and wheel 75 to contact 88^a, thence to conductor 88 and through 96 and 95 to line 2, when 95 and 96 engage. The impulse for the calling-circuit from central to the subscribers' 45 stations is also controlled through the medium of wheel 75, for which purpose I have shown a conductor 99, leading from the conductor 1 to a contact 100, and 101 is a contact to make and break circuit with contact 100. Contact 101 is connected by a conductor 102 with a generator 103, (which may be a power-generator,) from which a conductor 104 leads to ground, being shown connected 50 with conductor 83. 105 is a rocker-arm pivoted at 106 and adapted to operate contacts 100 101, insulation 105^a being provided between 100 and 105. 107 is a projection carried by wheel 75 and adapted to operate 55 rocker-arm 105, projection 107 being shown at one side of tooth 75^a of wheel 75; but tooth 75^a extends beyond projection 107. The arrangement is such that tooth 75^a and projection 107 will cause rocker-arms 97 and 105 to 60 simultaneously close the circuit at 95 96 and at 100 101, and when projection 107 passes from rocker-arm 105 circuit through 100 101

will be broken before rocker-arm 97 leaves tooth 75^a, and thus before circuit through 95 96 is broken. Thus when plug 92 is placed in the aperture 93 appropriate to the station desired and the wheel 75 is turned in the direction of the arrow γ in the drawings switch 86 will be moved into engagement with contact 87 when said switch encounters said plug, 75 and when wheel 75 moves in the reverse direction (which may be by hand, clockwork, or otherwise) the teeth upon said wheel will operate rocker-arm 97 to cause the desired number of impulses to pass over line 2 and 80 establish a circuit for the signaling instrument in the station desired, as before described, and when projection 107 reaches rocker-arm 105 tooth 75^a will still hold the circuit closed at 95 96 of the opposing line 2, 85 during which time a signal will be produced in the desired station over a circuit, as follows: from ground 84, through 83 104, generator 103, 102, 101, 100, (101 and 100 being now in engagement,) and 99 to line 1, thence to the 90 station to be called—say C—thence through 15, signaling instrument 55, 56, 57, 58, (which are now held in engagement by current on line 2,) and 59 to ground 60, thus producing a call at the desired station. Projection 107 will next move from arm 105 to 95 break the calling-circuit, and thereafter tooth 75 will move from arm 97 to break the operating-circuit. The circuit over line 3 to restore the subscriber-selecting devices to their 100 normal condition is also controlled by the action of wheel 75, and the arrangement for this purpose is as follows: The line 3 at central is connected, as by a conductor 108, with a contact 109, that is normally out of engagement with but adapted to engage a contact 110, and 111 is a rocker-arm adapted to make and break circuit between contacts 109 110, and wheel 75 carries a projection 112, adapted to rock the arm 111, insulation being interposed between arm 111 and contacts 109. The arrangement is such that after tooth 75^a and projection 107 have moved away from rocker-arms 97 and 105, respectively, as wheel 75 passes toward the home-point the projection 112 will operate arm 111 to close the circuit at 109 110 of the restoring-line, whereupon the circuit will be from ground 84 through 83, battery 82 81 80 78 85 86 87 (86 87 being still in engagement) to 88^a, 88, 110, 120 109, and 108 to line 3 and thence to the subscribers' stations to restore the operated devices thereat, as before explained.

In order that there shall be no circuit from line 3 through contacts 24 and 25 and conductor 26 of jack 5 while a station is being called, I have provided a rocker-arm 113, shown pivoted at 114 and adapted to make and break circuit between contacts 24 25, a projection 115 being carried by wheel 75 to 125 operate said rocker-arm, and the position of this projection is such that when wheel 75 has been moved from the home-point said projection will move away from arm 113, and

thus break circuit at 24 25, and after projection 112 has passed from arm 111 and wheel 75 reaches the home-point projection 115 will again engage arm 113 to keep circuit normally closed at 24 25. It will be understood that projections 107, 112, and 115 and the arms 105, 111, and 113 will be in such positions relatively to each other that the projections will only engage the appropriate rocker-arms at the proper times.

From the foregoing description it will be understood that when wheel 75 is moved from the home point circuit at 24 25 will first be broken and that the projections 107 112 and 15 the appropriate teeth of the wheel will pass under the rocker-arms, and that when the wheel is returned to the home point an impulse or impulses will first be sent over the operating-line 2 to operate the selecting devices 20 of the subscribers' stations to close the circuit of the signaling instrument thereat with line 1, that when the circuit of said signaling instrument has been so established the proper impulse will be sent over line 1 to 25 operate the same, that thereafter an impulse will be sent over the restoring-line 3 to restore the operating devices at the stations to their normal conditions and break the circuit of the selected signaling instrument, and that 30 thereupon switch 86 will engage stop 91 to break circuit at 86 87, and projection 115 will come to rest under arm 113 to restore the circuit at 24 25. It will also be understood that a tooth on wheel 75 corresponds to each station 35 on a party-line and that for each tooth that passes under rocker-arm 97 an impulse will be sent over the party-line 2. For instance, if the first station on a party-line is to be called, plug 92 will be inserted in the 40 appropriate hole 93 and the wheel turned until switch 86 engages said plug and is moved into engagement with contact 87, and tooth 75^a will pass under arm 97, so that as the wheel returns to the home point one impulse 45 will be sent over line 2 to close the circuit of signaling instrument 25 thereat. If station C (the second station on the party-line) is to be called, plug 92 will be placed in the appropriate hole 93 and wheel 75 can turn until 50 tooth 75^a and the next tooth 75^b pass under rocker-arm 97, and so on for as many stations as there are on a party-line between the central office and the station to be called, including the latter station.

55 I do not limit my invention to the precise details of construction shown and described, as they may be varied without departing from the spirit thereof. For instance, a return-wire can be used in place of the grounds 60 shown.

Having now described my invention, what I claim is—

1. A telephone system comprising a central office, a plurality of subscribers' stations, a 65 conductor leading from central to said stations, telephone instruments in each station,

and electrically-operating devices in each station for connection with said conductor and arranged to permit the supporting-lever of the receiver to establish a circuit for the latter if the circuit over said conductor is closed and to prevent the lever from establishing such circuit for the receiver if the circuit is broken, a second conductor leading from central for said stations, means at the stations 75 to connect said conductors, and means at central to be operated when the circuit of said conductors is closed to break the circuit of the first-mentioned conductor.

2. A telephone system comprising a central 80 office, a plurality of subscribers' stations, a conductor leading from central to said stations, telephone instruments in said stations, electrically-operating devices in each station normally out of circuit with said conductor 85 but adapted to be placed in circuit therewith by the movement of the receiver-supporting lever, said devices being arranged to permit full movement of said lever when the circuit over said conductor is closed at central and to 90 prevent such movement of the lever if said circuit is broken at central, a second conductor leading from central for said stations, means at the stations to connect said conductors, and means at central to be operated when the 95 circuit of said conductors is closed to break the circuit of the first-mentioned conductor.

3. A telephone system comprising a central office, a plurality of subscribers' stations, a conductor leading from central to said stations, telephone instruments in said stations, electrically-operating devices in said stations located on a normally open branch line leading from said conductor, means to close the branch line by the movement of the receiver- 100 supporting lever, said electrically-operating devices being arranged to permit the full movement of said lever when the circuit over 105 said conductor is closed at central and to prevent such movement of said lever when said circuit is broken at central, a second conductor leading from central for said stations, means at the stations to connect said conductors, and means at central to be operated when the 110 circuit of said conductors is closed to break 115 the circuit of the first-mentioned conductor.

4. A telephone system comprising a central office, a plurality of subscribers' stations, a conductor leading from central to said stations, telephone instruments in said stations, a normally open branch line in each station leading from said conductor, a contact to be operated by the receiver-supporting lever to make and break the circuit of the branch line, and electrically-operating devices connected 120 with said branch line arranged to permit the full movement of said lever when the circuit over said conductor is closed at central and to prevent such movement of said lever if said circuit is broken at central, a second conductor leading from central for said stations, 125 means at the stations to connect said conductors, and means at central to be operated when the circuit of said conductors is closed to break 130 the circuit of the first-mentioned conductor.

tors, and means at central to be operated when the circuit of said conductors is closed to break the circuit of the first-mentioned conductor.

5. In a telephone system a central office, a plurality of subscribers' stations, a conductor leading from central to said stations, telephone instruments in said stations, a normally open branch line in each station leading from said conductor, a contact to be operated by the receiver-supporting lever to make and break the circuit of the branch line, a magnet located on each branch line, a detent to be operated by said magnet, said detent in its normal position serving to check the full movement of said lever, and a contact to be engaged by said lever to close the circuit of the branch line, whereby when the circuit of said conductor is closed at central said magnet will operate the detent to permit the lever to make a full movement and when the circuit is broken at central said detent will prevent the lever from making a full movement, a second conductor leading from central for said stations, means at the stations 25 to connect said conductors, and means at central to be operated when the circuit of said conductors is closed to break the circuit of the first-mentioned conductor.

6. A telephone system comprising a central office, a plurality of subscribers' stations, a plurality of conductors leading from central to said stations and normally connected at central, one of said conductors being normally connected to ground at central, electrically-operating devices connected therewith at central arranged to break said ground, and devices at each station to join said conductors thereat in a closed metallic circuit, and arranged to prevent the formation of such 35 closed metallic circuit when the ground at central is broken.

7. A telephone system comprising a central office, a plurality of subscribers' stations, a plurality of conductors leading from central to said stations and normally connected together at central, one of said conductors being normally connected to ground at central, electrically-operating devices connected therewith at central arranged to break said ground, 45 other contacts at central connected with said conductors to be broken by the operator at central, devices at each station to join said conductors in a closed metallic circuit, and arranged to prevent the formation of such 55 closed metallic circuit when the circuit at central is broken.

8. A telephone system comprising a central office, a plurality of subscribers' stations, a plurality of conductors leading from central 60 to said stations and normally connected together at central, one of said conductors being normally connected to ground at central, electrically-operating devices connected therewith at central arranged to break such 65 ground, other contacts at central connected with said conductors to be broken by the operator at central, devices at each station to

join said conductors thereat in a closed metallic circuit, said devices being arranged to prevent the formation of a closed metallic 70 circuit when the circuit at central is broken, and means at central to produce a call when the circuit between central and a station is closed.

9. A telephone system comprising a central 75 office, a plurality of subscribers' stations, a pair of conductors leading from central to said stations and normally connected at central, one of said conductors being connected to ground at central, electrically-operating devices at central connected with said conductors and adapted to break said ground, call-producing instruments at central adapted to be operated by current on said conductors, means at central to enable the operator there- 80 at to break the circuit to ground, telephone instruments in said stations, means for joining said conductors in a closed metallic circuit through said telephone instruments, and electrically-operating devices in each station 85 adapted to prevent the formation of said closed metallic circuit when the ground at central is broken.

10. A telephone system comprising a central office, a plurality of subscribers' stations, a 95 plurality of conductors leading from central to said stations, one of said conductors being connected to ground at central, contacts at central to make and break the circuit to ground, a magnet and armature at central 100 connected to said conductors adapted to make and break said ground, telephone instruments at said stations, means at said stations to join the telephone instruments in a closed metallic circuit over said conductors, where- 105 by when said circuit is closed the magnet at central will break the ground, and means in said stations to prevent the closed metallic circuit from being established when said ground is broken.

11. A telephone system comprising a central office, a plurality of subscribers' stations, a pair of conductors normally connected at central and leading to said stations, one of said conductors being connected to ground at central, 115 contacts to make and break said ground, a local circuit at central having devices to produce a signal, a magnet connected with said conductors at central adapted to break said ground and close said local circuit, telephone instruments in said stations, means to connect them with said conductors in a closed metallic circuit whereby when they are so connected a signal will be produced at central, and electrically-operating devices in said stations to prevent said closed metallic circuit 125 from being established when the ground at central is broken.

12. A telephone system comprising a central office, a plurality of subscribers' stations, a 130 plurality of conductors normally connected at central and leading to said stations, one of said conductors being connected to ground at central, means at central to make and

- break said ground, a jack at central connected with said conductors and adapted to break the normal circuit of said conductors when a plug is inserted therein, telephone instruments at the subscribers' stations, means for connecting them in a closed metallic circuit over said conductors, and means in each station to prevent said circuit from being established when the ground to central is broken.
13. A telephone system comprising a plurality of stations, a plurality of conductors leading thereto, one of said conductors being divided into normally grounded sections in each station, a magnet on the section that leads into a station, said magnet having two poles, an armature for each pole, a normally open branch in each station from one of said conductors adapted to be closed to ground by a contact operated by one of said armatures,
- 15 a branch leading to the telephone instruments in each station from a contact adapted to be operated by the other armature to break the circuit, said contact being connected in each station with another of said conductors, said armatures being connected together and contacts to cause two sections of the first-mentioned circuit to be joined in a station by the operation of said armatures.
14. A telephone system comprising a plurality of stations, a plurality of conductors leading to said stations, one of said conductors being normally broken into sections in said stations, a magnet in each station connected with the section that leads into the station, said magnet having two poles, armatures to be operated by said poles and contacts to be operated by said armatures, another of said conductors being normally closed through contacts in said stations, said armatures being arranged to join two sections of

the first-mentioned circuit together and break the second-mentioned circuit into sections, a magnet in each station, and devices operated by one of said armatures for connecting said magnet with the section of the second-mentioned circuit that is formed by the first operation of the armature, whereby when said magnet is operated it will restore the parts to their normal conditions.

15. A telephone system comprising a plurality of stations, a plurality of conductors leading to said stations, one of said conductors being broken into normal sections leading to ground in said stations, a magnet on the section that leads into a station, said magnets each having two poles and a pair of armatures one of which is adapted to break the ground from the section and make connection with the conductor on the side of the magnet opposite the ground, one armature being in normal connection with the section of the conductor leading from the station, said armature having a contact normally connected with the section leading into the station and adapted to establish a temporary ground in said section to be broken when the magnet is deenergized, another conductor being normally closed in each station and having contacts adapted to be made and broken by one of said armatures, and a magnet for said armature arranged to be placed in circuit with the section of said conductor leading into a station by the initial action of said armature, said magnet being arranged to attract said armature to restore the through-circuit of said conductor.
